UPSETTING MECHANISM

Richard Lester Wilcox, Waterbury, Conn., assignor to The Waterbury Farrel Foundry and Machine Company, Waterbury, Conn., a corporation of Connecticut

Application May 18, 1942, Serial No. 443,407

10 Claims. (Cl. 10—12)

This invention relates to new and useful improvements in upsetting mechanism, more particularly to mechanism for holding a workpiece in proper relation to the tools during the action thereof and for clearing the punch of the workpiece if held therein.

In headers, upsetting machines or the like, a workpiece is conventionally upset by companion tools, one a die and the other a punch. These tools function by moving one toward the other, generally the punch, the workpiece being presented to the die, and while held thereby is subjected to pressure blows by one or more punches successively moved into line therewith. In the upsetting mechanism herein shown, two punch blows are contemplated, the workpiece being partially upset by the first blow and completed at the second blow. After the punch has partially upset the workpiece, the latter, upon occasion, remains in the punch and is withdrawn from the die. This is abnormal, as the workpiece should remain in the die and the punch withdrawn therefrom. The position of each punch after withdrawal is shifted and the next succeeding punch is moved into line with the die and engages the workpiece as it travels toward the die, provided the workpiece is still in the die. If, however, the workpiece has been withdrawn from the die by the first punch and remains therein, it will strike the tools or some part of the machine during the next forward movement of the punch, frequently breaking the tools and stopping the machine by jamming the workpiece in an abnormal position. In such case, production is delayed by the length of time it takes for the operator to separate the workpiece from the tools, this latter usually being accomplished by driving or drilling it out of its obstruction position, and if broken, to remove and replace the broken tools. To prevent this action is an object of the invention. This is accomplished by associating mechanism with the punch which will prevent the workpiece from being withdrawn from the die and retained in the punch, but if perchance it is withdrawn and retained, it will be ejected therefrom. This invention is particularly applied as illustrated and described in connection with the so-called spring punch, wherein the punch is movably mounted within the punch holder and engages the die prior to the completion of the forward stroke of the gate, during which time the punch is at rest.

It is an object of this invention to provide an improved spring punch and mechanism in connection therewith that will hold the workpiece rigid in the die against movement during a por-

tion of the withdrawal action of the gate and punch. Other objects will become apparent from the following description and the accompanying drawing.

To these ends the invention consists in the upsetting mechanism, having certain details of construction and combinations of parts, as will be hereinafter described and more particularly pointed out in the claims.

Referring to the drawing, in which like numerals of reference indicate like parts in the several figures:

Figure 1 is a fragmentary view of a portion of an upsetting mechanism, header or the like, having this improved mechanism associated therewith, the parts in section being taken generally upon a plane that extends through the centers of both punches;

Figure 2 is a view of the punch sleeve and some adjacent parts;

Figures 3 and 4 are views of the backing plate; and

Figure 5 is a perspective detail view of the punch upon a relatively enlarged scale.

In the drawing, the numeral 10 indicates the gate of a header, upsetting machine or the like, movably mounted in a frame 11; 49 the fabricating die; and 50 the knockout pin. Slidably mounted on the face of the gate is a carrier slide 12, upon which are the backing plates 13 and 14.

Adjustable relatively to the carrier slide 12, and the backing plates 13 and 14, are the punch holders 15 and 16, in the former of which is a punch 17, held rigid by any convenient and well known means, and in the punch holder 16 is a spring punch, shown herein as constructed with a sleeve 18, having a chamber 19 in its rear end with a slot 20 extending through the wall thereof, and in register with a slot 21 in the punch holder 16. Slidably mounted within the sleeve 18 is a punch 22 having an opening 23 therethrough, and upon the exterior is a shoulder 24, formed at the junction of two diameters thereof. The larger of these diameters is substantially the same as the chamber 19, and the relative outward position of the punch is determined by engagement of this shoulder with the end wall of the chamber substantially as shown in Figure 1. The inner face of the punch has an angular portion 51 that increases the open space in the chamber 19 upon one side of the center thereof. The punch 22 is held against rotation in the sleeve 18 by a pin 25 fixed in the sleeve and projecting into a recess 26 in the larger diameter of the punch. Movably mounted within the

opening 23 of the punch 22 is a pin 27, having a head 41, which in one position enters the recess 23 at the inner end of the opening 23.

Within the punch holder 16, in rear of the sleeve 18, is a backing plate 29, upon the inner face of which are lips 30 which project into notches 31 in the rear end of the sleeve 18 and thus hold the backing plate and sleeve against relative rotation. The backing plate 29 is held against rotation by a pin 32, which is in the punch holder 16 and projects into a notch 33 in the backing plate. In the outside wall of the larger diameter of the punch 22 are a plurality of notches 34, illustrated herein as three in number. These notches are preferably arranged substantially as shown in Figures 2 and 5, one being substantially opposite the slot 20, and the others substantially 90° upon each side thereof. Within each recess, and surrounding a pin 35, fixed in the backing plate 29, is a compression spring 36, which operates to urge the punch 22 outwardly. This action is limited by the engagement of the shoulder 24 with the end wall of the chamber 19 in the sleeve 18 in the manner hereinbefore described. Heretofore only one spring has been utilized in a spring punch. If such spring breaks the punch becomes inoperative, with possible injury to the punch and associated parts, and damage to succeeding workpieces, until the break is discovered. In this spring punch having a plurality of springs, such adverse conditions cannot prevail.

Journalized upon a pin 37, fixed in a lug 38 on the punch holder 16, is a rock lever 39, one arm of which projects through the slots 20 and 21, with the head 40 thereon in the chamber 19, and in line with the head 41 of the pin 27. By this structure the lever may function without interfering with the operation of the punch 22 or the yielding means (springs 36) by which the punch 22 is moved relatively to the sleeve 18. One arm of this rock lever projects rearwardly from the punch holder and straddles a pin 42 slidably mounted in a screw plug 43, threaded into and closing the open end of a hole 44 in the carrier slide 12. Between the head 45 on the pin 42 and the screw plug 43 is a spring 46, and on the outer end thereof are the lock nuts 47, which bear against the arm of the lever 39. During movement of the carrier slide 12 across the face of the gate 10, the outer end of the pin 42 engages a lug 48 on the gate, and thus positively moves the pin 42 in one direction, imparting a rocking movement to the lever 39, causing the head 40 thereon to move in the chamber 19 toward the outer end of the sleeve 18 and push the pin in advance thereof.

The pin 27, when in its rearmost position, is backed up by the head 40 of the rock lever 39, which also is in engagement with the backing plate 29. As the gate 10 moves forward, that portion of the work-piece projecting beyond the fabricating die 49 enters the opening 23 in the spring punch 22 and continues such entry until the face of the spring punch engages the fabricating die 49. The spring punch remains stationary in this position, but the gate, punch holder and pin 27, continue their forward movement, during which time the pin 27 exerts the required pressure on the workpiece and upsets that portion thereof outside of the fabricating die into a cone or other desired shape. When the pin 27 is in its foremost position and for the first portion of the return movement of the gate, the lever 39, under the tension of the spring 46, applies sufficient

pressure to the pin and through it to the work-piece to hold the workpiece in the fabricating die. During the first portion of the movement of the gate away from the fabricating die the spring punch 22 and pin 27 remain stationary until the end wall of the chamber 19 engages the shoulder 24 on the punch. Thereafter, the punch travels with the punch holder, the pin remains stationary, and the spring punch is drawn over the pin, thereby stripping the punch from the workpiece.

The operation performed by the spring punch and fabricating die usually cones or upsets that portion of the workpiece outside of the face of the fabricating die 49. After withdrawal of the spring punch the second punch 17 is carried into alignment with the fabricating die. During the next forward movement of the gate the second punch completes the workpiece by changing the upset portion thereof into the required finished shape.

Within the scope of the following claims the invention may be embodied in various other forms without departing from its spirit.

What is claimed is:

1. In mechanism of the character described, a punch holder, a punch movably mounted therein and having an axial opening therethrough, yielding means to urge the punch in one direction with respect to the punch holder, a pin within said opening, and means independently movable with respect to the punch and yielding means for imparting movement to the pin independently of said punch and yielding means.

2. In mechanism of the character described, a punch holder having an opening through one wall thereof, a sleeve within the punch holder having a chamber in one end thereof and having an opening in register with the opening in the punch holder, a punch movably mounted within the sleeve, a pin movable within the punch, a rock lever mounted upon the punch holder and having a part extending through both of said openings and engaging said pin so as to actuate the latter when the rock lever is moved relative to said punch holder, and means for actuating the said rock lever.

3. In mechanism of the character described, a movable gate, a slide transversely movable on the gate, a punch holder associated with the slide, a fabricating die, a spring biased punch mounted in the punch holder, a pin movably mounted within the punch, and means actuated by the gate for moving the pin a predetermined distance within the punch independently of the latter and for maintaining the same in a stationary position with relation to the fabricating die during a portion of the return movement of the gate.

4. In mechanism of the character described, a movable gate, a slide movable on the gate, a punch holder associated with the slide, a fabricating die, a punch mounted in the punch holder, means normally biasing the punch to one position in the punch holder, a pin movably mounted within the punch, movable means carried by the punch holder having a part engaging the pin and having a second part disposed in the path of the gate whereby movement of the latter will actuate said means and thereby the pin a predetermined distance within the punch and to maintain the pin in a predetermined stationary position with relation to the fabricating die during a portion of the return movement of the gate.

5. In mechanism of the character described, having a punch holder, a spring biased punch mounted therein, a movable pin within the punch, a fabricating die, and means for moving the punch

holder toward and away from the fabricating die; the combination therewith of means for holding the pin rigid against the workpiece in the fabricating die during movement of the punch holder away from the fabricating die and while the punch is held in engagement with the fabricating die and workpiece by said punch biasing means.

6. In mechanism of the character described having a punch holder, a spring biased punch mounted therein, a movable pin within the punch, a fabricating die, and means for moving the punch holder toward and away from the fabricating die; the combination therewith of means for holding the pin rigid against the workpiece in the fabricating die during movement of the punch holder away from the fabricating die and while the punch is held in engagement with the fabricating die and workpiece by its biasing means, comprising in part, a pivoted lever, one portion of which is between the end of the pin and a rigid part of the punch holder, and means for actuating the lever and thereby the pin in timed relation with the movement of the spring biased punch.

7. In mechanism of the character described having a punch holder, a spring biased punch mounted therein, a movable pin within the punch, a fabricating die, and means for moving the punch holder toward and away from the fabricating die; the combination therewith of means for holding the pin rigid against the workpiece in the fabricating die during movement of the punch holder away from the fabricating die and while the punch is held in engagement with the fabricating die and workpiece by its biasing means, comprising in part, a pivoted lever having a portion disposed between the end of the pin and a rigid part of the punch holder, and another portion extending outwardly beyond the punch holder, and means for actuating the lever and thereby the pin in timed relation with the movement of the spring biased punch, the lever actuating means having engagement with that portion of the lever which extends beyond the punch holder.

8. In mechanism of the character described; a gate; a slide movable on the gate; a punch holder associated therewith; a fabricating die; a spring biased punch mounted in the punch holder; a pin mounted within the punch for relative axial move-

ment with respect to the latter; means for moving the pin within the punch and maintaining the same in a stationary position with relation to the fabricating die during a portion of the return movement of the gate; means for projecting the pin axially forward of its said stationary position during movement of the slide, and means for actuating said first and second means.

9. In mechanism of the character described, having a punch holder, a spring biased punch having a pin movably mounted therein, a fabricating die, and means for moving the punch holder toward and away from the fabricating die; the combination therewith of means for holding the movable pin against the workpiece in the fabricating die during the movement of the punch holder toward the fabricating die and while the spring biased punch is urged into engagement with the fabricating die and workpiece and for projecting the pin outwardly of the punch after the latter has begun its movement away from the fabricating die.

10. In mechanism of the character described having a punch holder, a spring biased punch mounted within the punch holder, a pin movably mounted within the punch, said punch having both synchronous and independent movement relative to the punch holder, a fabricating die, means for moving the punch holder toward and away from the fabricating die; the combination therewith of means for holding the pin against a workpiece in the fabricating die during a portion of the movement of the punch holder away from the fabricating die, comprising in part a pivoted lever, one portion of which is disposed between the end of the pin and a rigid part of the punch holder and another portion of which projects beyond the latter, and means for operating the lever in timed relation with the movement of the spring biased punch, the lever actuating means having engagement with that portion of the lever which lies beyond the spring biased punch, the operation of the parts being such that while the pin is held against the workpiece and during the latter portion of the movement of the spring biased punch away from the workpiece, the spring biased punch is drawn over the pin to thereby strip the punch from the workpiece.
